UNITED STATES PATENT OFFICE.

GÜNTHER PHILIP WILD, OF PHILADELPHIA, PENNSYLVANIA.

EXPANSIBLE ROLLER.

1,072,067.

Specification of Letters Patent.

Patented Sept. 2, 1913.

Application filed November 18, 1912. Serial No. 732,024.

To all whom it may concern:

Be it known that I, GÜNTHER PHILIP WILD, a citizen of the United States, residing in the city and county of Philadelphia, 5 State of Pennsylvania, have invented a new and useful Expansible Roller, of which the following is a specification.

My invention consists of an expansible roller for winding a web of paper, textile 10 material or similar flexible material, which may be quickly and positively contracted to enable it to be withdrawn from the finished roll.

It further consists of improved means in 15 such roller, whereby the segmental plates which constitute the periphery of the roller are simultaneously moved and parallelism of such plates maintained.

It further consists of improved means for 20 locking such segmental plates in their expanded position.

It further consists of improved means for exerting a permanent inward tension upon 25 such segmental plates.

It further consists of other novel features 30 of construction, all as will be hereinafter fully set forth.

The annexed drawings and the following description set forth in detail, one mechan- 35 ical form embodying the invention; such detail construction being but one of various mechanical forms in which the principle of the invention may be used.

In said annexed drawings—Figure 1 repre- 40 sents an axial section of my improved expansible roller. Fig. 2 represents a trans- verse section on the line $x-x$ in Fig. 1. Fig. 3 represents a transverse section on the line $y-y$ in Fig. 1. Fig. 4 represents a trans- 45 verse section on the line $z-z$ in Fig. 1. Fig. 5 represents a transverse section on the line $a-a$ in Fig. 1. Fig. 6 represents a trans- verse section on the line $b-b$ in Fig. 1. Fig. 7 represents an axial section of the sliding 50 collar and a portion of a sleeve, illustrating another form of spring for the locking de- vice for the shaft and sleeves.

Similar numerals of reference indicate 55 corresponding parts in the figures.

Referring to the drawings, the reference 60 numeral 1 indicates a shaft, having at one end removable means for rotating it, such as a handle, 2, having its end removably inserted through a diametrical hole in the shaft. 65 Cylindrical sleeves, 3 and 4, are located near 55 the ends of the shaft, which is rotatable in

the axial bores, 5 and 6, of the sleeves, and said sleeves have annular flanges, 7 and 8, and one of the sleeves has a hub, 9, which is polygonal or otherwise adapted to be held 60 by a wrench, spanner or similar tool. Similar intermediate sleeves, 10, without flanges, are located upon the shaft, having axial bores, 11, their number and spacing being regulated according to the length of the 65 roller and the weight of the roll to be wound upon the same. A cylinder, 12, fits upon said sleeves and is secured to the same by screws, 13. All of the sleeves have enlarged 70 axial bores or recesses, 14, and a series of circular holes, 15, are formed through the sleeves and cylinder,—eight of such holes being illustrated at each sleeve. Collars, 16, have a free fit within the recesses in the sleeves, and are secured to the shaft by 75 means of pins, 17, or similar fastening means. A series of round recesses, 18, are formed in the periphery of each of said collars, and register with the holes in the sleeves and cylinder. Anti-friction balls, 19, 80 have a rolling fit in the holes of the sleeves and cylinder and can drop into the recesses of the collar, the curves of which are described on a larger radius than that of the 85 balls.

A number of plates, 20, segmental in cross-section, form the periphery of the roller, and have radial guide-pins, 21, slidable in radial bores, 22, in the cylinder and sleeves. 90 Four segmental plates and four pins in each set are illustrated, but such number may be varied according to requirements. Collars, 23, have axial bores, 24, and are located upon the shaft which may turn within the bores. Two of such collars are here dis- 95 closed, but the number of the collars may be varied according to the length of the roller. Each collar has a series of notches, 25, in its periphery, corresponding in number to that of the peripheral sections or 100 plates, and flat springs, 26, have their ends secured in said notches. Said springs are so tempered that they tend to bend inward, and screws, 27, are secured in the peripheral sections and pass through holes in the cylinder and have their ends screwed into the free ends of the springs, so that the springs will act to draw the peripheral sections inward toward the axis of the roller. A collar, 28, is secured by a feather, 29, and a groove, 30, to 105 rotate with and slide upon the shaft, and one face of said collar has an annular series of 110

notches or depressions, 31, in the present instance eight, corresponding to and registering with the lands or raised portions, 32, between the round recesses 18 in the collars 16. The opposite face of the adjoining sleeve has pins, 33, in the present instance two, secured in it, and the ends of said pins engage two of the notches in the face of the collar 28. One end of a coil-spring, 34, upon the shaft, bears against a washer, 35, bearing against the face of the slideable collar, and the other end of such spring bears against a washer, 36, bearing against the face of the next adjoining rigid sleeve, so that the pins are normally held, while the balls are resting upon the lands or raised portions of the recessed or cam collars, in engagement with the notches, preventing accidental unlocking of the parts of the roller as adjusted, while the relative turning of the shaft and sleeves by additional force, will overcome the tension of the spring and allow the rounded ends of the pins to slip out of the shallow notches and permit the balls to drop into their respective recesses in the collars, where they will serve as locks.

In Fig. 7 is illustrated another form of spring for the sliding locking-collar 28. The collar is in this case formed with a diametrical groove, 37, in its face, and a curved leaf-spring, 38, is inserted through a slot, 39, in the shaft and has its ends engaging said groove. The spring will hold the collar to rotate with the shaft, and will force the notched face of the collar against the pins.

In practice, the roller is expanded by gripping the hub at one end of the roller against rotation and rotating the shaft by means of the handle, until the balls in the several sleeves are raised out of the round recesses in the peripheries of the collars rigid upon the shaft and rest upon the lands between such recesses. As the balls are thus simultaneously forced outward, they force the peripheral sections or segmental plates outward, thus giving the roller its greatest diameter. When the shaft is turned to perform this function, the collar sliding upon and rotating with the shaft will bring two of its notches or depressions to register with the pins upon the adjoining sleeve, and, by the action of the spring, force said notches into engagement with such pins, thereby locking the shaft and peripherally recessed collars, the sleeves and cylinder, and the peripheral sections together. The web may now be wound upon the roller, which usually is revolved by resting as an idler upon two driven rollers. When the roll of web is complete and removed from whatever machine produces and winds the web, or merely winds the web, and it is desired to remove the roller from the center of the web, said

roller is contracted by again turning the shaft while holding the sleeves and cylinder against rotation, bringing the recesses in the collars to register with the holes in the sleeve and cylinder and with the balls therein, which will then enter such recesses by the peripheral sections being drawn inward by the springs which thus contract the roller so that the latter may be withdrawn from the roll wound upon it.

The intermediate sleeves, recessed collars and springs may have their number increased or decreased according to the length of the roller and the weight of the roll to be wound upon the same, and the number of peripheral sections, holes in the sleeves, recesses in the collars, springs and locking pins and notches may be varied according to the requirements placed upon the roller.

By providing the cam-collars or recessed collars and the balls interposed between such collars and the peripheral sections, and connecting such collars that they will all move in unison, and by confining the balls so that they will all be acted upon by such cam-collars in unison, an expansible roller is produced in which the expansion and contraction of the sections is simultaneous and parallel throughout the entire length of the roller.

The notched collar and the pins upon the intermediate sleeve retain the relative position of the sleeves, cylinder and peripheral sections to the shaft and collars, when the balls rest upon the lands or raised portions of the latter when the roller is expanded. When the roller is contracted, the balls resting in the recesses of the collar will lock the parts.

Other modes of applying the principle of my invention may be employed for the mode herein explained. Change may therefore be made as regards the mechanism thus disclosed, provided the principles of construction set forth, respectively in the following claims are employed.

Having thus described my invention, what I claim as new and desire to secure by Letters Patent, is:—

1. An expansible roller, comprising peripheral sections forming the periphery of the roller, an axial rotatable shaft, sleeves upon said shaft and formed with axial recesses and with holes in the walls of such recesses, means for connecting said sleeves, collars secured upon the shaft within the recesses in the sleeves and formed with rounded recesses in their peripheries corresponding to the holes in the sleeves, and anti-friction balls in such holes and interposed between the collars and the peripheral sections.

2. An expansible roller, comprising peripheral sections forming the periphery of the roller, resilient means for drawing such sections toward the axis of the roller, an

axial rotatable shaft, sleeves upon said shaft and formed with axial recesses and with holes in the walls of such recesses, means for connecting said sleeves, collars secured upon the shaft within the recesses in the sleeves and formed with rounded recesses in their peripheries corresponding to the holes in the sleeves, and anti-friction balls in such holes and interposed between the collars and the peripheral sections.

3. An expansible roller, comprising peripheral sections forming the periphery of the roller, an axial rotatable shaft, a hollow cylinder within said sections, sleeves secured 15 within said cylinder and loose upon said shaft and formed with axial recesses and with holes in the walls of said recesses, collars secured upon the shaft within the recesses in the sleeves and formed with rounded recesses in their peripheries corresponding 20 to the holes in the sleeves, and anti-friction balls in such holes and interposed between the collars and the peripheral sections.

4. An expandible roller, comprising peripheral sections forming the periphery of the roller, resilient means for drawing such sections toward the axis of the roller, an axial rotatable shaft, a hollow cylinder within said sections, sleeves secured within said cylinder and loose upon said shaft and formed with axial recesses and with holes in the walls of said recesses, collars secured upon the shaft within the recesses in the sleeves and formed with rounded recesses in their peripheries corresponding to the holes in the sleeves, and anti-friction balls in such holes and interposed between the collars and the peripheral sections.

5. An expansible roller, comprising peripheral sections forming the periphery of the roller, resilient means for drawing such sections toward the axis of the roller, an axial rotatable shaft, a hollow cylinder within said sections, sleeves secured within said cylinder and loose upon said shaft and formed with axial recesses and with holes in the walls of said recesses, collars secured upon the shaft within the recesses in the

sleeves and formed with rounded recesses in their peripheries corresponding to the holes 50 in the sleeves, means for detachably locking said shaft and collars to said sleeves, and anti-friction balls in such holes and interposed between the collars and the peripheral sections. 55

6. An expandible roller, comprising peripheral sections forming the periphery of the roller, means for radially guiding such sections in their movement toward and from the axis of the roller, resilient means for drawing such sections toward the axis of the roller, an axial rotatable shaft, a hollow cylinder within said sections, sleeves secured within said cylinder and loose upon said shaft and formed with axial recesses and with holes in the walls of said recesses, collars secured upon the shaft within the recesses in the sleeves and formed with rounded recesses in their peripheries corresponding to the holes in the sleeves, and anti-friction balls in such holes and interposed between the collars and the peripheral sections. 60 65 70

7. An expansible roller, comprising peripheral sections forming the periphery of the roller, means for radially guiding such sections in their movement toward and from the axis of the roller, resilient means for drawing such sections toward the axis of the roller, an axial rotatable shaft, a hollow cylinder within said sections, sleeves secured within said cylinder and loose upon said shaft and formed with axial recesses and with holes in the walls of said recesses, collars secured upon the shaft within the recesses in the sleeves and formed with rounded recesses in their peripheries corresponding to the holes in the sleeves, means for detachably locking said shaft and collars to said sleeves, and anti-friction balls in such holes and interposed between the collars and the peripheral sections. 75 80 85 90
